W. B. CHURCHER

AUTOMOTIVE HEAD LAMP

Filed June 30, 1926

Patented July 10, 1923.

1,676,769

UNITED STATES PATENT OFFICE.

WILLIAM B. CHURCHER, OF CLEVELAND, OHIO, ASSIGNOR TO THE WHITE MOTOR COMPANY, OF CLEVELAND, OHIO, A CORPORATION OF OHIO.

AUTOMOTIVE HEAD LAMP.

Application filed June 30, 1926. Serial No. 119,764.

My invention relates to improvements in head lamps, and it relates particularly to head lamps employing illuminating bulbs having a lower voltage rating than the voltage of the battery or other source of current therefor. In many automotive vehicle electrical installations, comprising a source of current and one or more head lamps for the vehicle, it so happens that it is difficult to 10 commercially manufacture durable lamp filaments effective for all of the purposes intended, giving the lamp filaments the voltage rating of the source of current. For instance, in the so-called "tilt-ray" head lamp system, wherein a plurality of filaments having different focal characteristics relative to the lamp reflector, it has been found more expedient to manufacture the filaments for such a lamp bulb having a voltage rating of 15 substantially 6-8 volts, than to make them with a rating of 12-16 volts, which is the voltage range of the source of current commonly provided in many automotive vehicles. It is necessary, in such a case, to provide various expedients to insure that the voltage effective at the filament terminals is 20 within the rated voltage of the bulb filament, it being proposed heretofore to place a pair of like filaments of a pair of head lamps in series, so as to divide the impressed voltage of the battery or other source of current between the lamp filaments. 25 Such an arrangement is undesirable for the reason that filaments vary in voltage ratings and time of responsiveness to the effect of heating current, with the result that occasionally one filament of a pair serially connected, being more quickly responsive to the heating effect of the current, will be 30 overheated before the other filament is sufficiently heated. Also, at the same time, it is undesirable that both filaments should fail, due to a burning out of the one filament of two serially connected filaments. 35 It has also been proposed to provide a resistance unit in series with the pairs of multiplied filaments, but this arrangement has the disadvantage of impressing an undesirable high voltage upon the terminals of 40 the surviving filament should the other filament of the pair be burned out or its circuit inadvertently opened. Therefore, it has been found that an individual resistance unit must be provided for each filament, 45 making four resistance units for a pair of

lamp bulbs, each having two filaments. It is very undesirable to place these resistance units at the switch for controlling the circuit of the lamps, and it is likewise undesirable that it be positioned at other points 60 on the automotive vehicle heretofore proposed, so far as I am aware.

My present invention, therefore, has for an object the provision of a resistance unit in a head lamp casing so related to the other 65 head lamp parts that undesirable effects of the unit are avoided.

Another object of my invention is to provide an improved mounting for a head lamp casing containing resistance unit. 70

Another object of my invention is to provide in a unitary structure a head lamp unit comprising a pair of resistances, one for each of the lamp filaments and so positioned that electrical connections may readily be made 75 between the supply electrical conductors and the head lamp bulb filaments contained within the lamp casing.

Another object of my invention is to provide an improved "tilt-ray" head lamp having relatively low voltage lamp filaments operable from a source of current of higher voltage. 80

Other objects of my invention and the invention itself will be readily apparent by reference to the following description of an embodiment of my invention, in which description like parts will be indicated by like reference characters. 85

Referring to the drawings: 90

Fig. 1 shows, front elevational view partly in section of a head lamp, embodying my invention, portions being therein shown as broken away;

Fig. 2 shows a section taken on the line 95 2-2 of Fig. 1;

Fig. 3 is a fragmentary elevational view of certain parts comprising a modified resistance element; and additional supporting 100 means therefor;

Fig. 4 shows a fragmentary elevational view of a modified support for an embodiment of my invention;

Fig. 5 shows a perspective view of a 105 mounting spring employed in the said embodiments;

Fig. 6 shows a diagrammatic view of a circuit arrangement in which the resistance of Figs. 1, 2 and 4 may be included. 110

Fig. 7 is a partial diagrammatic view of a modification.

Referring now to the different figures of drawing, in all of which like parts are designated by like reference characters, at 1, I show a lamp casing having, in the embodiment illustrated, tubular side walls 3, a rear end wall 2, and a front glass 4, the showing of which is omitted in Fig. 1, secured at the 10 front of the casing together with the flanged rim 5 of a reflector 6 by a flanged clamping ring 7 in any suitable way, but so that the front glass and reflector are clamped at their rim portions to the mouth of the casing and supported thereby. The reflector rim is centrally perforated at 8 to admit the cylindrical lamp socket element 9 which supports an electric bulb 10 whose base 11 is projected within the socket.

20 The socket and base have the usual focusing and electrical circuit extending provisions, so that these will not be explained here, being well known, except that it may be stated that with a "tilt-ray" bulb, such as 25 the bulb 10, having a plurality of filaments 40 and 41, the common terminal for the filaments is connected to the tubular metallic band 13 encircling the tube base and the other terminals each individually to one of 30 the filaments are extended rearwardly to electrical connecting terminals 14 and 15, the terminal 14 being extended to the filament 40 and the terminal 15 being electrically extended to the filament 41. It will 35 also be understood that one of the filaments, such as the filament 40, will be so positioned relative to the focal point of the reflector 6 that the rays of light from the filament 40 will be projected from the reflector in a direction substantially below the horizontal, and is used for the so-called "dim" light, the filament 41 is so disposed that the rays of light will be horizontal and slightly below horizontal producing the so-called 45 "bright" or "driving" light.

In the appended claims it will be understood that wherever I have used the term "tilt-ray", I use it as definitive of that type of electric lamp having a plurality of filaments which may be selectively heated by directing current through one or the other of said filaments selectively and comprising an individual terminal for each filament, whereby different electric circuits for the 50 different filaments may be had, and which lamp bulb is capable of being placed in such a focal position relative to a concave reflector receiving the bulb, that the different filaments thereof will, when selectively individually energized, cause the rays of light to be reflected from the reflector at different angles; that is the rays from one of the filaments will be "tilted" relative to the rays from another of the filaments.

55 I use the term "tilt-ray", therefore, in the

claims as being my choice of a term for an element of the claim having the above described properties and structure.

At 16, I show a support for the head lamp having a preferably convex crown 17, the head lamp being secured to such support crown by means of a bolt 18, whose head is disposed within the casing and supported by a lamp body stiffener 19, the stem of the bolt being projected through an opening in the 70 cylindrical wall of the casing, through the convex crown 17 of the support, a nut 21 being screw threaded on the end of the bolt, a bearing washer 22 being interposed between a lock washer 23 under the nut and the concave surface of the crown 17. Thus the crown 17 of the support having an enlarged opening 24 for permitting swivelling movements of the bolt 18, is clamped between the bearing washer 22 and the outer bearing portion 20 of the body stiffener 19. The engaging surfaces of the bearing washers and the crown are formed to effect a bearing contact.

75 The body stiffener element 19 has a face 80 engaging the outer surface of the cylindrical wall 3 and conforms to the form thereof, and is riveted at either end by a plurality of rivets 25 to the wall of the casing. The bolt receiving openings of the stiffener element and casing wall are preferably only 85 sufficiently large to receive the bolt, whereas the opening 24 for the crown 17 is sufficiently enlarged to permit swiveling of the head lamp upon the crown.

80 At 26, I show one of a pair of spring supports having base flanges 27 and a coil supporting apertured projection 28 extending from the opposite end of the support from the base flange and from the opposite side thereof. The base flanges are apertured at 95 52, so that the like support 26 may be oppositely disposed and carried on the body of the lamp walls 3 and riveted thereto together with the outer stiffener element 19 by 100 means of the rivets 25. The resistance unit is preferably of tubular form and is divided into two longitudinally spaced resistance portions, 50 and 51, each having a resistance coil therein, the one resistance coil being 105 shown at 111 and the other resistance coil being shown at 112. The resistance coils may be wound on a tube, as illustrated. The apertured projecting portions 28 of the springs 26 are adapted to project into the 110 tubular ends of the resistance unit, the spring 26 resiliently pressing against the ends of the tubular resistance unit sufficiently that the unit will be firmly held in place after 115 being positioned upon the springs.

120 Sometimes, I may provide a bolt 60 or other securing means passing through the aperture in the projections 28 of the springs and the tubular bore of the unit, although I preferably rely upon the spring pressure 125 130

of the springs to retain the unit in place. At 29, I show a tubular socket element projected through a wall of the lamp casing and supported thereby, and having an insulating block 30 disposed in its inner end with a pair of electrical circuit conducting rods 31 and 32 projected therethrough, electrical circuit conductors 43 and 44 leading from the terminal rods 31 and 32 to terminals of the resistance windings 111 and 112, respectively. The other terminals of the two windings are electrically connected, respectively, by circuit conductors 14 and 15 to filaments 40 and 41 of the lamp bulb. 10
15 The tubular socket element 29 is adapted to receive a plug 34 insertable within the socket to extend electrical connections from a pair of circuit conducting terminal contacts 33 to the terminal rods 31 and 32. 20 Springs 35 embedded within the block 30 each resiliently press the rods 32 and 31, respectively, against the terminal contact 33. The plug contact 33 is extended by an electrical circuit conductor 45 to the source of current supply for the lamp. The block and socket 34—29 respectively, are of any usual well known construction and are shown merely to illustrate the manner of extending the connection from such a socket through 25 30 the resistance coils and the lamp filaments.

Fig. 6 shows diagrammatically a circuit arrangement in which my invention may be embodied wherein at 65 I show a 12-volt battery and at 69 I show a switch blade moved from a normal position 70 to either of positions 71 and 72 whereby resistance 111 or 112 may be included in circuit with filaments 40 or 41 respectively. The value of resistance of the resistance coils will preferably 35 40 be made the same as the resistance of the filaments, when hot, in all cases where it is desired to operate 6-volt filaments, 40 and 41 from a 12-volt battery 65. According to Ohm's law, it will be possible to vary the 45 resistance according to the voltage of the battery and the resistance of the filaments when hot.

It will be noted that the tubular resistance coil unit, comprising resistance coils 111 and 112, has a sufficient area as to properly dissipate heat resulting from the flow of current through the resistances, and is mounted in such a way that the effect of such a heat will not be effective to injure the 50 55 reflecting surface of the reflector 6. The unit is placed relatively low in the casing and in the middle portion thereof, so that the flow of heated air upwardly therefrom will be circulatory to dissipate the heat rising from the coil against upper outer walls of the casing, and being chilled will follow the lateral walls of the casing to the space below the coil.

Fig. 7 shows a modification of my invention wherein the lamp 10 is insulated by an

insulating tube 81 from the socket 9, and a terminal 62 inserted within the tube 81 contacts with the metallic cap 11 of the lamp to which is connected the common terminal 63 of the lamp filaments 40 and 41. 70 In this way, the common return wire leading from the terminal 62 to ground at 64 lead through a single resistance coil 60' which is effective to reduce the current flowing through either one of the filaments 40 or 41 75 which may at any time be included in circuit with the battery 65 in any way such as by a switch 66 having alternate contacts 67 and 68.

Having thus described my invention in a specific embodiment, I am aware that numerous and extensive departures may be made from the embodiment herein illustrated and described but without departing from the spirit of my invention. 80 85

I claim:

1. In a head lamp, the combination with a casing, a lamp bulb having a plurality of filaments, a resistance unit comprising a pair of resistances, a body stiffener element contacting with a portion of the walls of the casing, securing means adapted to rigidly secure the stiffener element to the inner wall of the casing and supporting means for said unit secured in place within the casing by 90 said securing means, a connection terminal means adapted to make electrical connection with circuit conductors exterior of the casing, said terminal means being carried in a wall of the casing and adapted to extend electrical connections therethrough, and electric circuit conductors interconnecting the said resistances with the said filaments and the said terminal means. 95

2. In an electric head lamp, the combination with a head lamp bulb comprising an electric filament, a lamp casing comprising a back and side walls, a reflector having a forwardly disposed concave reflecting surface and a glass disk disposed in front of the reflector, said disk and said reflector secured at their edges to the side walls of the casing, said bulb being carried on the concave reflector, a connection element carried on a wall of the casing to the rear of the reflector and adapted to extend electrical connections from the exterior to the interior of the casing, a resistance unit disposed in the space between the reflector and the rear casing wall, a support for the head lamp, means to reinforce the casing wall at its portions wherein connection is made between said wall and the support, and a supporting arm for the unit, carried by said reinforcing means, adapted to support the unit out of contact with the walls of the casing and the reflector, and an electrical circuit connection interconnecting the bulb, resistance unit, and electric connection element. 105 110 115 120 125

3. In an electric head lamp, the combina- 130

tion with a head lamp bulb, a lamp casing comprising a back and side walls, a reflector having a forwardly disposed concave reflecting surface and a glass disk disposed in front of the reflector, said disk and said reflector secured at their edges to the side walls of the casing, said bulb being carried on the concave reflector, a connection element carried on a wall of the casing to the rear of the reflector and adapted to extend electrical connections from the exterior to the interior of the casing, a resistance unit disposed in the space between the reflector and the rear casing wall, a support for the head lamp, means to reenforce the casing wall at its portions wherein connection is made between said wall and the support, a supporting arm for the unit carried by said reenforcing means adapted to support the unit out of contact with the walls of the casing and the reflector, and an electrical circuit connection interconnecting the bulb, resistance unit, and electric connection element, said bulb having a pair of lighting filaments, said unit having a pair of resistance elements, each one of said elements being connected in serial circuit with a different one of said filaments by said electric circuit conductors.

30 4. In an electric head lamp, the combination with a head lamp bulb comprising an electric filament, a lamp casing comprising a back and side walls, a reflector having a forwardly disposed concave reflecting surface and a glass disk disposed in front of the reflector, said disk and said reflector secured at their edges to the side walls of the casing, said bulb being carried on the concave reflector, a connection element carried on a wall of the casing to the rear of the reflector and adapted to extend electrical connections from the exterior to the interior of the casing, a resistance unit disposed in the space between the reflector and the rear casing wall, a support for the head lamp, means to reenforce the casing wall at its portions wherein connection is made between said wall and the support, a pair of supporting arms for the unit carried by said reenforcing means adapted to support the unit out of contact with the walls of the casing and the reflector, and an electrical circuit connection interconnecting the bulb, resistance unit, and electric connection element, each of said arms being rigidly secured to the casing and to said reenforcing element at one of its ends, said resistance unit being of tubular form, the other end of each supporting arm making supporting engagement with an end of said unit.

55 5. In an electric head lamp, the combination with a head lamp bulb comprising an electric filament, a lamp casing comprising a back and side walls, a reflector having a forwardly disposed concave reflecting sur-

face and a glass disk disposed in front of the reflector, said disk and said reflector secured at their edges to the side walls of the casing, said bulb being carried on the concave reflector, a connection element carried on a wall of the casing to the rear of the reflector and adapted to extend electrical connections from the exterior to the interior of the casing, a resistance unit disposed in the space between the reflector and the rear casing wall, a support for the head lamp, means to reenforce the casing wall at its portions wherein connection is made between said wall and the support and a pair of supporting arms for the unit carried by said reenforcing means adapted to support the unit out of contact with the walls of the casing and the reflector, and an electrical circuit connection interconnecting the bulb, resistance unit, and electric connection element, each of said arms being rigidly secured to the casing and said reenforcing element at one of its ends, said resistance unit being of tubular form, the other end of each supporting arm making spring pressed engagement with an end of said unit, said tubular unit being recessed at its ends to receive projections of the said arms.

60 6. In a head lamp, a "tilt-ray" bulb therefor, a concave reflector supporting at its center the said bulb, a head lamp casing having rear and side walls, said reflector secured at its edges to forwardly disposed portion of the casing side walls, an electric resistance unit supported by the casing intermediate the reflector and a side and rear casing wall, means adapted to extend electrical circuit connections through a wall of the casing, an electrical circuit connection interconnecting said means and the dual filaments of said "tilt-ray" bulb, and a yoke element supported by the casing at an intermediate portion and removably supporting the unit by its arms.

65 7. In a head lamp, a "tilt-ray" bulb therefor, a concave reflector supporting at its center the said bulb, a head lamp casing having rear and side walls, said reflector secured at its edges to forwardly disposed portion of the casing side walls, an electric resistance unit supported by the casing intermediate the reflector and a side and rear casing wall, means adapted to extend electrical circuit connections through a wall of the casing, an electrical circuit connection interconnecting said means and the dual filaments of said "tilt-ray" bulb, and means comprising a pair of supporting arms supported by the casing at an intermediate portion and removably supporting the unit by its arms.

In testimony whereof I hereunto affix my signature this 9th day of June, 1926.

WILLIAM B. CHURCHER.
